UNITED STATES PATENT OFFICE.

JOSHUA B. WILSON, OF MANILA, ALABAMA.

STEEL TIE.

Application filed February 10, 1922. Serial No. 535,469.

To all whom it may concern:

Be it known that I, JOSHUA B. WILSON, a citizen of the United States of America, residing at Manila, in the county of Clarke 5 and State of Alabama, have invented new and useful Improvements in Steel Ties, of which the following is a specification.

The object of the invention is to provide a simple and efficient railroad tie of a construction and involving materials designed to economize in the use of wood without dispensing with the advantages derived from the employment of wood as a means of constituting the bed for the rail, it having 10 been sufficiently demonstrated in practice that the cushioning property of wood is advantageous in the support of railway rails, and with this object in view the invention consists in a construction and combination 15 of parts of which a preferred embodiment is shown in the accompanying drawings, wherein:—

Figure 1 is a perspective view of a tie embodying the invention.

Figure 2 is a longitudinal sectional view of the same.

Figure 3 is an enlarged sectional view of one end of the tie showing a rail in position thereon.

The tie consists of a metallic casing 10 of which the ends 11 are preferably hinged as indicated at 12 and are secured in their closed positions by hasps 13 engaged with lugs 14 fitted with cotter pins, and in the 15 ends of the casing are fitted fillers 15 consisting of blocks of suitable wood limited in their inward movement by stops 16 upset from the walls of the casing, said blocks being exposed at their upper sides by cut 20 away portions 17 of the casing to provide transverse rail seats 18. The openings in the casing to expose the rail seats are extended downwardly at the side walls of the casing to afford clearance and permit of a yielding of the filler blocks under the weight imposed upon the rails so that the full elasticity of the filler blocks may be utilized, and the replacement of these blocks when worn or injured can be readily effected 25 through the accessible ends of the casing.

The side edges of the casing bounding the openings 17 therein are notched as indicated at 19 for the reception of spikes 20 indicated in Figure 3 and the engagement of these spikes with the rails and said notches serves 35 to interlock the parts so that relative displacement is prevented.

The intermediate portion of the casing between the adjacent ends of the filler blocks is adapted for the reception of weighting 40 objects as a filler for example of concrete or stone, if the use thereof is deemed necessary in order to secure the desired rigidity or solidity under special conditions of the road bed or ballast, it being obvious that 45 such supplemental filler may be introduced before positioning one of the terminal filler blocks.

Having described the invention, what is claimed as new and useful is:—

A tie comprising a hollow metallic casing which is rectangular in transverse section, the top wall of the casing being provided with transversely disposed openings the end 50 portions of which extend down into the side walls of the casing, the top wall of the casing being provided at the edges of said openings with notches adapted to receive spikes, stops mounted upon the inner surface of the bottom wall of the casing and 55 spaced from the ends thereof and disposed transversely of the said bottom wall and having their upper edges spaced from the under surface of the top wall of the casing, end panels hinged to the ends of the bottom 60 wall of the casing and adapted to close against the ends of the top and side walls thereof, angular hasps hinged to the free edge portions of the panels and adapted to engage over the end portions of the top wall 65 of the casing and blocks fitting in the end portions of the casing between the stops and the panels whereby the hasps and the stops are disposed at the opposite diagonal corners of the blocks and the openings and 70 spike notches are disposed over the upper intermediate portions of the blocks.

In testimony whereof I affix my signature.

JOSHUA B. WILSON.
